HYDROTHERAPY POOL

David K. Cavenah, Los Angeles, Calif. (4238 Shady Glade Ave., P.O. Box 1174, Studio City, Calif. 91604)

Filed May 14, 1970, Ser. No. 22,988

Term of patent 14 years

Int. Cl. D23—02; D24—02

U.S. Cl. D83—1

FIG. 1 is a perspective view of a hydrotherapy pool showing my new design;

FIG. 2 is a top view thereof;

FIG. 3 is a bottom view thereof; and

FIG. 4 is a side elevational view thereof.

I claim:

The ornamental design for a hydrotherapy pool, substantially as shown.
